EARTH MOVER AND DUMPER Laurie Neilson, Orinda, and Robert E.
Stevens, Lafayette, Calif.

Application August 10, 1953, Serial No. 373,313

2 Claims. (Cl. 37—132)

This invention relates to equipment for picking up, transporting, and dumping relatively large quantities of earth or similar matter, and is more particularly directed towards a unitary apparatus of this nature which may be readily attached to a transport vehicle for movement over the ground.

In practically all construction projects, a certain amount of grading must be done, either in taking quantities of earth from one location, filling in other locations, or moving the earth between such locations. It should be apparent that the use of several different types of equipment, such as steam shovels for digging, and dump trucks for transporting, is not economically sound, and in view thereof, certain self-propelled mechanisms have been developed which are capable of performing the multi-functions of grading, transporting and dumping. Unfortunately such mechanisms as are presently available are very large, and likewise very expensive, thereby making their use only warranted on large projects. Also, due to the capital investment involved as well as the maintenance costs, this type of machine cannot be easily obtained or kept by the average small contractor.

Accordingly, it is an object of the present invention to provide a simple inexpensive apparatus which may selectively be utilized to grade, transport or dump a quantity of earth.

Another object of our invention is to provide apparatus of the character described which is relatively small in size and which may conveniently be attached to a source of locomotion for movement over the ground.

A further object of this invention is to provide apparatus of the above type in which manually operable means are provided for moving the earth carrying portion from and between its three utilitarian positions.

Yet another object of the invention is to provide novel control mechanisms in the above type of equipment including means actuated by the movement of the apparatus for effecting selective movement.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings:

Figure 1 is a side elevational view of the apparatus of the present invention.

Figure 2 is a top plan view of the apparatus shown in Figure 1.

Figure 3 is a sectional view taken on line 3—3 of Figure 2.

Figure 4 is an end elevational view taken substantially in the plane indicated by line 4—4 of Figure 3.

Figure 5 is a sectional view taken substantially in the plane indicated by line 5—5 of Figure 3.

2

Figure 6 is a sectional view taken substantially in the plane indicated by line 6—6 of Figure 3.

Figure 7 is a view similar to Figure 1, but indicating the earth holding bracket in its grading and dumping positions.

Broadly speaking, and as hereinabove mentioned, the apparatus of the present invention is designed to be pulled by any suitable vehicle, and can be selectively positioned to: first, grade the earth by scraping the same and depositing the loose earth in a receptacle or bucket portion of the machine; second, transport the earth to some other location; and, third, dump the earth at some convenient location. Also, as will be presently explained, suitable mechanism is provided to move the apparatus into the above mentioned positions with a minimum of effort and without requiring any power other than that created by the movement of the apparatus over the ground.

Referring particularly to Figures 1, 2 and 7 of the drawings, our machine includes a frame assembly, generally indicated by the numeral 12, said frame, for purpose of illustration, being shown as a pair of parallel spaced longitudinally extending elements 13, suitable cross-bracing 14, a pair of posts 16 extending vertically from adjacent the rear ends of elements 13, a pair of diagonal braces 17 interconnecting the upper ends of the posts with a forward portion of elements 13, and a suitable tow hitch 18 at the front or forward end of the frame. As here shown, the various component parts of the frame are shown as structural channels, although any other suitable metal or wood construction could be utilized.

The frame is mounted for movement over the ground by means of a pair of wheels 19 mounted on a transverse axle 21 which is journaled in a pair of bearings 22 carried by the frame elements 13 adjacent the rearward end of the latter. As in the case of most two wheeled trailers, the forward end of the frame will normally rest on the ground, and when it is desired to use the apparatus, the hitch 18 will be raised to the position shown in the drawings, attached to a tractor or other motive vehicle, and the unit may then be readily pulled or pushed over the ground.

Mounted on the frame between the elements 13 is an earth carrier or bucket 26 which is designed and positioned to receive, transport and dump the earth as may be required. As here shown, the bucket is in the form of a box with an open top and open at its front and rear ends. The bottom 27 and opposed sides 28 of the bucket are formed of metal plate, and, if necessary, bracing 29 may be utilized to prevent deformation of such sides, with other suitable bracing along the bottom to render greater structural strength to the bucket. As will be noted, on the outer surface of each side 28, we provide plates 31, and by means of pivot pins 32, journaled in bearings 33 carried by elements 13, and secured to such plates, the entire bucket may be pivoted about an axis substantially normal to the longitudinal axis of the frame assembly. In this manner, the bucket may be moved to and between a first or grading position, indicated in solid lines in Figure 7, and a second or dumping position, indicated by dot-dash lines in said figure.

A front gate 36 and rear gate 37 are used to provide a removable closure for the respective open ends of the bucket, such gates being preferably hinged to the bucket sides as indicated at 38 and 39. No particular means are shown for maintaining the gates in their closed or open position, as such means are well known in the art and form no part of the present invention.

Mounted at the leading lower edge of the bucket is a scraper blade 41 extending for substantially the entire width of the bucket. In view of the fact that the pivot

pins 32 are disposed adjacent the rear end of the bucket, and rearwardly of the center of gravity thereof, the bucket will, under the influence of gravity, normally assume the solid line position of Figure 7 with the blade engaging the ground. By pulling the apparatus in a forward direction, the blade will bite into the ground or earth, and the loosened earth will be deposited in the bucket. Naturally, during this loading operation, the front gate will be open and the rear gate will be closed. By means of mechanism presently to be described, the bucket may be raised to a horizontal position, as shown in Figure 1, and the apparatus moved to any other desired location. Then, the bucket may be tilted rearwardly to substantially a forty-five degree slope, the rear gate opened and the contents dumped out.

The mechanism for effecting the foregoing pivotal movements of the bucket 26 may assume a wide variety of types, but for reasons of economy and simplicity in operation, the controls now to be described are particularly well suited for such operations. With reference to Figure 3, it will be noted that the vertical posts 16 carry a transverse horizontally disposed main drive shaft 51, such shaft preferably extending beyond the left hand post, as viewed in Figure 3. A drum 52 is telescopically engaged with the greater portion of the length of the shaft 51. The drum serves as a spindle for a pair of cables 53, one end of each cable being secured to the drum, and the other ends of the cables being secured to the bucket sides by means of brackets 54. In this manner, when the drum is coupled to the shaft 51, rotation of the latter will cause the cables to be selectively wound and unwound upon the drum, and as the cables are connected to the bucket forward of its center of gravity, such variation in cable length will result in the bucket being moved between the extremes of movement illustrated in Figure 7 of the drawings.

A simple clutch mechanism is utilized to selectively place drum 52 in and out of operative engagement with the drive shaft. One end of drum 52 is provided with one clutch element 56 having teeth 57 at the distal end thereof. Shaft 51 carries the other clutch element 58 which is movable axially along the shaft to selectively be engaged with and disengaged from element 56. Naturally, when the clutch is engaged, the drum will rotate with the shaft and effect the aforementioned cable movement.

To effect such axial movement of clutch element 58, an actuating rod 59 is provided generally parallel to and subjacent to shaft 51. This rod is slidably supported in a plurality of apertured brackets 61 which in turn are mounted on a transverse structural member 62 disposed between posts 16. The rod is normally urged to the right as viewed in Figure 3 by means of a spring 63 and the distal end of the rod is provided with one cam 64 which engages a second cam 65 secured to the outer surface of post 16. Cam 64 carries a manually engageable actuating handle 68, and rotation of the handle will cause rotation of cam 64 and effect axial movement of rod 59. Particularly, when the widest portions of the cams are caused to be engaged, the rod will move to the left and effect engagement of the clutches as will presently be explained.

Means are provided for moving clutch element 58 to the right and into operative engagement with clutch element 56 upon movement of the rod 59 to the left. Such means includes an arm 71 pivotally secured to a collar 72 carried in a peripheral groove in the rod, an intermediate portion of the arm being pivotally attached to a bar 73 carried by post 16, and the end portion bifurcated as indicated at 74. The bifurcated end portions are attached by pins 76 to a frame 77, the latter having diametrically opposed lugs which are slidably received in a peripheral groove 78 provided in the hub 79 of the element 58. Thus, the frame will remain stationary during

rotation of the shaft, but serves to slide the clutch element into engagement when required.

Shaft 51 may be rotated by any suitable means, but here again, for reasons of simplicity, we prefer to utilize a "free" source of power to accomplish this function. As here shown, the wheel axle 21 is provided with a sprocket 81, with the drive shaft 51 being likewise provided with a sprocket 82. A drive chain 83 is connected to the sprockets whereby the drive shaft will be rotated so long as the apparatus is in motion. Obviously, this arrangement will not permit tilting of the bucket when the apparatus is not moving, but by reducing the size of the drive shaft sprocket, only a small amount of movement will be required to impart the small amount of rotation necessary to move the bucket.

Also, in order to provide for uni-directional movement of the drive shaft, a ratchet and pawl arrangement as best seen in Figures 4 is provided. As will be seen, the sprocket 82 is provided with a ratchet wheel 86 and a hub 87 carrying one or more spring loaded pawls 88 carried by the shaft 51.

As an added safety feature, brake means are provided on drum 52, which positively locks the latter against rotation except when the clutch elements are engaged. As here shown, a brake shoe 91, having a lining 92, encircles a disk 93 provided on the drum. Normally, the brake is placed in operative condition by means of a cam 94 which urges the lowermost of the brake shoe extensions 96 towards the upper extension against the resistance of a spring 97. Cam 94 is carried on an arm 98 pivotally attached to a collar 99 carried on rod 59 in much the same manner as collar 72. Then, as the rod is moved to the left as previously explained, the movement of arm 98 will rotate cam 94 permitting the springs to expand the brake shoe and thereby permitting the drum to again be freely rotated.

From the foregoing description of the exemplary apparatus illustrated in the drawings, the details of construction and operation should be clear. It will be appreciated that our improved earth moving mechanism can be economically constructed and easily controlled. If desired, a cord or arm 101 may be fastened to the control handle 68 so that the driver of the vehicle towing the apparatus can cause desired tilting movement of the bucket without leaving his vehicle. Also, if desired, stop lugs may be placed on the bucket engageable with portions of the frame structure to limit the degree of forward and rearward tilting of the bucket. In operation, shortening of the cables 53 by winding or reeling the same about drum 52 will cause the bucket to be pivoted counterclockwise as viewed in Figure 7 to first acquire a generally horizontal disposition. Further winding of the cables will tilt the bucket to its dumping position wherein the load is dumped through the rear gate 37. Unwinding of the cables will permit the bucket to gravitationally assume its digging position illustrated by solid lines in Figure 7 of the drawings.

We claim:

1. Earth moving equipment comprising a longitudinally extending frame, an axle mounted on said frame and having ground engaging wheels thereon, a bucket, means pivotally securing said bucket to said frame along a transverse axis disposed rearwardly of the center of gravity of said bucket, a transversely disposed drive shaft, means for rotating said drive shaft upon rotation of said axle, a drum member axially aligned with said drive shaft and having flexible means wound therearound and attached to said bucket forwardly of its center of gravity, a clutch element carried by said drum member, a second clutch element carried by said shaft, an actuating rod, link means interconnecting said rod and one of said clutch elements, said rod being normally positioned to maintain said clutch elements in disengaged relation, and cam means for axially moving said rod and urging said clutch

elements into engagement whereby said drum will be rotated upon movement of said wheels over the ground in a forward direction and said flexible means will be reeled upon said drum to pivot the forward portion of said bucket upwardly.

2. Apparatus as set forth in claim 1 including means for preventing drum rotation upon movement of said wheels in a contra direction.
